UNITED STATES PATENT OFFICE.

BALTIS P. LUKENS AND ISADORE S. DIEHL, OF ALLENTOWN,
PENNSYLVANIA.

VEHICLE-BRAKE.

No. 848,668.

Specification of Letters Patent.

Patented April 2, 1907.

Application filed May 22, 1906. Serial No. 318,127.

To all whom it may concern:

Be it known that we, BALTIS P. LUKENS and ISADORE S. DIEHL, of Allentown, in the county of Lehigh and State of Pennsylvania, have invented certain new and useful Improvements in Vehicle-Brakes, whereof the following is a specification, reference being had to the accompanying drawings.

Our invention relates to brakes for vehicles, and particularly to that class of brakes which are adapted to engage the surface upon which the vehicle runs.

The form of our invention hereinafter described comprises a brake-shoe which is pivotally suspended from the car-frame in close proximity to the rail on which the car runs and which is provided with a removable face-plate carrying a plurality of replaceable friction-studs so sharpened as to dig into said rail when forced into contact therewith.

We have chosen to illustrate our invention as applied to an ordinary street-railway car; but it is to be noted that it is applicable to other types of vehicles.

Our invention comprehends the various novel features of construction and arrangement hereinafter more definitely specified.

In the accompanying drawings, Figure I shows in side elevation the forward portion 30 of a car to which our invention is applied. Fig. II is a rear elevation of those parts which include our invention. Fig. III is a central vertical longitudinal section of the brake-shoe. Fig. IV is an inverted plan view of 35 said brake-shoe. Fig. V is a sectional view of one form of the friction-studs employed in said shoe. Fig. VI is an elevational view of another form of friction-stud employed in said shoe for the same purpose.

In said drawings, 1 is the forward end of a car, from the underframing of which depend hangers 2, carrying a rock-shaft 3, which is provided with arms 4, corresponding in vertical planes to the rails upon which the vehicle runs. To each of said arms 4 is pivoted a link 5, which is in turn pivoted to the brake-shoe 6. As best shown in Fig. I, the arm 4 and link 5 thus form a toggle-joint, whereby the rotation of the rock-shaft 3 in the direction indicated by the arrow in Fig. I forces the brake-shoe into frictional engagement with the rail.

Upon the shaft 3 is secured the chain-wheel 7, which is connected by the chain 8 to

the lower end of the brake-rod 9, arranged to 55 be rotated to wind said chain thereon and to thereby rotate the wheel 7 and shaft 3 to depress the brakes in opposition to the tension of the spring 10, which normally tends to maintain the brake mechanism in inoperative 60 position.

In order to maintain the brake-shoes in proper operative relation with the rails, there is pivoted to the forward end of each of said shoes a rod 12, whose length is conveniently adjusted by the turnbuckle 13 and whose forward end is pivoted to its respective hanger 15, depending from beneath the forward end of the platform of the car.

Referring now to Fig. III of the drawings, 70 wherein the pivotal connection with the shoe 6 of the supporting-link 5 and rod 12 are clearly shown, it may be seen that the brake-shoe proper consists of a metal block having a plate 20 set within a recess 21 in its lower 75 face and united to it by bolts 22, 22. Said plate 20 is provided with a plurality of apertures 23, through which the friction-studs 24 and 25 extend, each being provided with a head 26, which is countersunk within the 80 plate, whereby they are held in position.

The lower end of each of the studs, of which we have shown two forms, projects through the friction-plate so as to bear directly upon the rail when the brake is applied. In one form the lower end of the stud 24 is recessed centrally, as shown in Fig. V, which provides a sharpened circular rim arranged to contact with the rail. In the other form (shown in Fig. VI) the stud 25 is pointed. 85 These studs may be formed of hardened steel or other suitable metal and are readily made in large quantities, and as they are readily replaced it is obvious that as soon as those carried by the brake become worn 90 down so as to lose their holding power others may be substituted.

The brake-shoe 6 is further provided with a side flange 28, depending from its inner edge and arranged to slide along the inner side of 100 the rail to maintain said shoe at all times in proper longitudinal relation with said rail.

We do not desire to limit ourselves to the precise details of construction and arrangement herein set forth, as it is obvious that 105 various modifications may be made therein without departing from the essential features of our invention.

We claim—

1. In a vehicle-brake, the combination of the brake-shoe; of means arranged to press said shoe against the rail upon which the vehicle runs; a removable face-plate for said shoe; and a plurality of replaceable friction-studs held in place by said face-plate, substantially as set forth.
  2. In a vehicle-brake, the combination with a brake-shoe supported in proximity to the surface traversed by said vehicle, and located between a wheel and the end of the vehicle; of a shaft journaled above said shoe; an arm on said shaft; a link connecting said shoe and arm; and a rod extending from said shoe to the under side of the vehicle, whereby the shoe is maintained in proper relation to the vehicle; and means arranged to shift said shaft to extend said shoe into engagement with said traversed surface, substantially as set forth.
  3. In a vehicle-brake, the combination with a brake-shoe; of a removable face-plate for said shoe; and a plurality of edged frictional studs held in place by said face-plate, substantially as set forth.
  4. In a vehicle-brake, the combination with a brake-shoe; of a removable face-plate
- for said shoe; and a plurality of edged frictional studs passing through and secured in place by said face-plate, substantially as set forth.
5. In a vehicle-brake, the combination with a brake-shoe; of a plate secured to said shoe; a plurality of shouldered apertures in said plate; and shouldered edged frictional studs seated in said apertures, arranged to frictionally engage a relatively movable surface, when said shoe is shifted, substantially as set forth.
6. In a vehicle-brake, the combination with a brake-shoe; of a plate secured to said shoe; a plurality of pointed studs; heads on said studs opposed to said points and arranged to be engaged by said plate; and means arranged to shift said shoe to engage said points with a relatively movable surface.

In testimony whereof we have hereunto signed our names, at Allentown, in the State of Pennsylvania, this 18th day of May, 1906.

BALTIS P. LUKENS.
ISADORE S. DIEHL.
